W. HARRIS.

CARD RECEIVER.

No. 16,072.

Patented May 5, 1885.

UNITED STATES PATENT OFFICE.

WILLIAM HARRIS, OF BALTIMORE, MARYLAND.

DESIGN FOR A CARD-RECEIVER.

SPECIFICATION forming part of Design No. 16,072, dated May 5, 1885.

Application filed March 28, 1885. Term of patent 7 years.

To all whom it may concern:

Be it known that I, WILLIAM HARRIS, a citizen of the United States, residing at Baltimore city and State of Maryland, have invented and produced a new and original Design for Card-Receipters or Ornamental Dishes, of which the following is a specification, reference being had to the accompanying photographic illustration, forming a part thereof.

10 The photograph represents a perspective view of the newly-designed card receiver or dish.

It consists of the representation of a cloth or rug in disorder, and a small dog holding a

portion of the same in his mouth. The leading feature of the design is the co-ordinated association of the dog and the rug or cloth, producing a striking and attractive effect.

What I claim is—

The design for a card-receiver or fancy dish herein shown and described, the same consisting of the representation of a rug or cloth and a dog holding a portion of the same in his mouth.

WILLIAM HARRIS.
